UNITED STATES PATENT OFFICE.

BARNES NEVILLE WALLIS AND CHARLES DENNISTON BURNET, OF WESTMINSTER, ENGLAND, ASSIGNEES TO AIRSHIP GUARANTEE COMPANY, LIMITED, OF WESTMINSTER, ENGLAND, A BRITISH COMPANY.

RIGID AIRSHIP.

Application filed August 19, 1927, Serial No. 214,023, and in Great Britain September 17, 1926.

This invention relates to rigid airships of the kind which comprise longitudinal girders extending from the bow to the stern of the ship and transverse frames which intersect the longitudinal girders at intervals and which frames are usually of the form of polygonal rings.

In the past it has not been possible to revolve or determine in an accurate manner the various forces acting at different points throughout the framework of an airship and the latter has accordingly been more or less of a redundant structure comprising a large number of relatively small members which have been interconnected in such a manner that the forces set up are distributed indeterminately throughout the component parts of the structure. As the exact nature of the forces acting on any particular member or group of members in a highly redundant structure can only be estimated with an approximate degree of exactitude, it has been impossible to reduce their weight to the minimum while preserving any required factor of safety.

The object of the present invention is to reduce to the minimum the number of component parts in the structural framework of an airship and, by an equal or proportional distribution of the load throughout the members of a framework specially designed to support it, to secure a reduction in weight and produce a simplified structure in which any necessary factors of safety which it is desired to obtain in each component part can be predetermined with exactitude.

In order to obtain this result it is necessary in the first instance to ensure an equal distribution of the forces throughout constituent parts of the longitudinal girders and the transverse frame members so that no undue stresses or bending moments arise and to this end and according to the present invention the centroid of each transverse frame member as also that of the intersecting longitudinal girders are made coincident or approximately coincident at a point. The lift wires and shear wires alone, together in certain cases with the transverse bracing wires or bulkhead wiring, are connected to, or approximately to, the point of coincidence of the centroids of the intersecting frames and girders. According to one arrangement

both the longitudinal girders and the intersecting transverse frame members are triangular in cross section, the apex of the longitudinal girder pointing outwards and the apex of the transverse frame pointing inwards or vice versa and, at their points of intersection, the longitudinal girders are built into and secured to the transverse frames with their centroids coincident with those of the transverse frame, the point of intersection forming the centre of a structure the extremities of which lie on the surface of an imaginary sphere or spheres.

In previous systems, it has been common to make connections from the mesh wiring which supports and encloses the gas containers direct to the longitudinal members, from whence the lifting forces were in turn transferred to the transverse frame members. Owing to the fact that the load is transferred to the longitudinal members as a beam it is difficult in this system to estimate the stresses set up in the framework.

In order to secure a more direct application of the lifting forces to the framework of the airship it is proposed to attach the mesh wiring to the framework at the points of intersection of the longitudinal girders and the transverse frames.

In cases, for example, where the longitudinal girders are of triangular cross section, each corner of the triangle being constituted by a tube, a member (hereinafter termed a longitudinal spider) may be provided having three radial arms, each arm being provided at its outer extremity with a semi-circular socket which accommodates a tubular socket piece projecting laterally on each side of the spider. Each end of the socket piece is provided with a screw thread on which an internally screw threaded collar is mounted. The end tubular members of each section of the longitudinal girder are also provided with screw threads and, by bringing them in alignment with the socket pieces on the spider the ends of a pair of contiguous girder sections can be detachably secured to the sockets on the spider by means of the aforesaid internally screw threaded collars. The base of each triangular transverse frame member, where at each corner of the polygon the frame is intersected by the longitudinal girder, is secured to the longitudinal spider by a corre-

sponding structure (hereinafter termed a transverse spider) so that its centroid is coincident with the centroid of the longitudinal girder. To restrain angular displacement of the transverse spider relatively to the longitudinal spider the transverse spider may be connected to the longitudinal spider at two points.

In order that the said invention may be clearly understood and readily carried into effect, the same will now be described more fully with reference to the accompanying drawings, in which:—

Figure 1 is a section through one of the transverse frame members of an airship at the point where the said frame intersects a longitudinal girder, the transverse frame members being of triangular cross-section with the apex pointing inwards towards the centre of the ship, and the longitudinal girders being of triangular cross-section with the apex pointing outwards.

Figure 2 is a sectional end view of Figure 1.

Figure 3 shows a suitable form of coupling device for attaching the shear and lift wires to the centroid of the longitudinal spider, and

Figure 4 is a section on the line 4—4 of Figure 3.

Fig. 5 is a perspective view of the combined longitudinal and transverse spiders, and

Fig. 6 is a view of a portion of a transverse frame with the adjacent circumferential wiring to illustrate the position and function of the lift and shear wires, the longitudinal members and bulkhead wiring being omitted for the sake of clearness.

The longitudinal girders and the transverse frame members are of triangular cross-section as aforesaid, each corner of the triangle being constituted by a tube, and the tubes being interconnected by means of bracing members (not shown). A, A, are the tubes forming part of the longitudinal girder and B, B are the tubular corner members of the transverse frame. The longitudinal spider has three radial arms C, C, C, attached at their inner ends to a triangular connecting piece C⁴, each arm being provided at its outer extremity with a semi-circular socket C' which accommodates a tubular socket piece C² projecting laterally on each side of the spider. Each end of each socket piece C² is provided with a screw thread on which an internally screw threaded collar C³ is mounted. The ends of the tubular members A, A, of each section of the longitudinal girder are also provided with screw threads, and, by bringing them into alignment with the socket pieces C², C² on the spider C the ends of a pair of contiguous girder sections can be detachably secured to the socket pieces C² on the

spider C by means of the aforesaid internally screw threaded collars C³. The transverse spider is of triangulated configuration with the apex pointing inwards towards the axis of the ship and comprises three members E, E, E, the ends of which are located within three sockets E', E', E', each socket E' carrying a tubular socket piece E² projecting laterally on each side of the spider E. Each end of each socket piece E² is provided with a screw thread on which an internally screw threaded collar E³ is mounted. The ends of the tubular members B, B, of each section of the transverse frame members are provided with screw threads and, by bringing them into alignment with the socket pieces E², E², on the spider E, the ends of a pair of contiguous transverse members can be detachably secured to the socket pieces E², E² by means of the screw threaded collars E³, E³. As indicated, one of the members E is cut in order to permit one of the arms C to pass through it, the portions of the member E being connected by side plates E⁴. The longitudinal spider C and the transverse spider E are secured to one another so that their centroids coincide at the point P. To restrain angular displacement of the transverse spider E relatively to the longitudinal spider C the former is secured to the latter at two points F and F'. In order to provide a degree of angular flexibility between the longitudinal girders A, A and the frame members B, B, the connections between the longitudinal and transverse spiders may be made sufficiently flexible by such means as the use of loosely fitting bolts. The provision of this slight degree of flexibility ensures that the deflections of the hull framework as a whole do not impose large racking actions upon the joints of the airship. As the intersecting longitudinal and transverse spiders C and E can, as aforesaid, be bounded by an imaginary sphere any variation in the angular relationship between the two spiders will not vary the point of coincidence of their centroids provided the same vertical relationship of the intersecting parts is not altered. The point of intersection of the centroids is arranged so that it occurs at the axis of the longitudinal spider and at this point, an axial opening C⁵ is provided through which end pieces G, G for the lift wires, and end pieces H, H for the shear wires are passed, the said end pieces being secured in position by a coupling device. A suitable form of coupling device is illustrated at Figures 3 and 4 and comprises a sleeve I to be fitted within the apertures C⁵ and through which the end pieces G, G and H, H for the lift and shear wires G' and H' are threaded, the wires being secured in place within the sleeve for example by means of swaging or of soft

metal J which is poured around the wires and allowed to set. Alternatively soft metal may be compressed around the wires or the wires may be secured in position by means 5 of a bolt carrying suitable fork ends for the reception of similar ends attached to the main cables. At each of their ends the said end pieces G, G and H, H carry turn-buckles to which the lift wires G' and the 10 shear wires H' are attached.

The aforesaid arrangement may be used in conjunction with the system of mesh wiring described in Patent No. 1,658,821 and/or the system of bulkhead wiring described in 15 co-pending patent application Serial No. 214,036, filed August 18, 1927 where a strop connects the bulkhead wiring to the point of attachment of the circumferential mesh wiring, and/or with the system of bulkhead 20 wiring described in co-pending application Serial No. 214,328 filed August 28, 1927, where the said wiring comprises taut and slack wires together with an axial restraint. In the embodiment illustrated L, L (Figures 25 1 and 2) are the slack catenary wires and M is one of the taut radial wires of the said bulkhead wiring described in application Serial No. 214,328 filed August 20, 1927, and N, N (Figures 1 and 6) are the strops 30 for connecting the bulkhead wiring to the circumferential mesh wiring as described in application Serial No. 214,036 filed August 18, 1927.

As will be seen from Fig. 6, the lift wires 35 G¹, the function of which is to transfer the buoyancy of the gas bags contained within the circumferential wiring to the rigid members of the structure, are attached to the points where the strops N join the circumferential wiring and pass immediately of 40 their length, by junction with the end pieces G, Figures 1 to 4, through the centroids P of the transverse members. Similarly the shear wires H¹, by means of end pieces H, 45 pass from the centroids in one transverse frame to those in the next, being crossed as indicated in Fig. 6 in order to brace the panels formed by the longitudinal and transverse frames.

In cases where the apex of each longitudinal girder points outwards as in the example illustrated the method of securing the outer cover in place, involving the use of tension wiring as described in English Patent No. 282,518, can also advantageously be employed either alone or in combination 55 with the arrangement described in English Patent No. 280,670 where each panel of the outer cover is detachably secured to the intersecting points of the longitudinal girders and transverse frames by means of catenaries.

What we claim and desire to secure by Letters Patent of the United States is:—

65 1. A rigid airship in which the centroids

of the transverse frame members and of the respectively intersecting longitudinal girders are made substantially coincident at a point, and lift wires and shear wires are connected to the intersecting transverse 70 frame members and longitudinal girders substantially at the said points of coincidence.

2. A rigid airship in which the longitudinal girders and the transverse frame 75 members are of triangular cross section, the apex of the longitudinal girders and the apex of the transverse frame members pointing in opposite directions and wherein, at their intersection, the longitudinal girders 80 are built into and secured to the transverse frames with their centroids coincident approximately at a point with those of the transverse frame members, and lift wires and shear wires are connected to the intersecting 85 transverse frame members and longitudinal girders substantially at the said points of coincidence.

3. A rigid airship as claimed in claim 1, 90 wherein intersecting longitudinal and transverse spiders having substantially coincident centroids are provided to which the longitudinal girders and the transverse frame members are attached.

4. A combined longitudinal and transverse spider for connecting the corresponding members in a rigid airship, wherein the longitudinal spider structure has three radial arms, each arm being provided at its outer extremity with a tubular socket piece 95 projecting laterally on each side of the spider to which the ends of the tubular portions of the longitudinal girders are attached.

5. A combined longitudinal and transverse spider for connecting the corresponding members in a rigid airship wherein the transverse spider structure is constituted by a triangulated structure which is attached, 100 preferably in a flexible manner, to the longitudinal spider, the tubular end members of the transverse frame members being connected to socket pieces carried by the said transverse spider.

6. A combined longitudinal and transverse spider for connecting the corresponding members in a rigid airship, wherein the longitudinal spider structure has three radial arms and the transverse spider structure is constituted by a triangular frame the 105 plane of which is at right-angles to that of the arms.

7. A combined longitudinal and transverse spider for connecting the corresponding members in a rigid airship as in claim 6, 110 in which one of the radial arms projects through one of the sides of the triangular frame.

8. A combined longitudinal and transverse spider for connecting the correspond- 115

ing members in a rigid airship as in claim 6, in which the centroids of the longitudinal and transverse spider structures are coincident.

5. 9. A rigid airship as claimed in claim 1, provided with longitudinal and transverse spiders and in which the bulkhead wiring is attached to the apex of the transverse spider.

10. A rigid airship as claimed in claim 1, ¹⁰ provided with longitudinal and transverse spiders and in which strops are provided at the apex of the transverse spider for connecting the bulkhead wiring to the circumferential mesh wiring.
